DESIGN FOR A HYDROPLANE

Antoine Gazda, Providence, R. I.

Application November 19, 1941, Serial No. 104,210

Term of patent 14 years

To all whom it may concern:

Be it known that I, Antoine Gazda, a citizen of no country, residing in Providence, county of Providence, State of Rhode Island, have invented a new, original, and ornamental Design for Hydroplanes, of which the following is a specification, reference being had to the accompanying drawing, forming a part thereof.

Fig. 1 is a plan view of a hydroplane showing my new design,

Fig. 2 is a side elevational view of the hydroplane shown in Fig. 1, and

Fig. 3 is a front elevational view of the hydroplane shown in Fig. 1.

I claim:

The ornamental design for a hydroplane, as shown.

ANTOINE GAZDA.
